DESIGN FOR A VENDING MACHINE CABINET

Peter Copeland, New York, N. Y., assignor, by mesne assignments, to Burgess C. Case, Plainfield, N. J.

Application November 3, 1947, Serial No. 142,281

Term of patent 7 years

(Cl. D52—3)

To all whom it may concern:

Be it known that I, Peter Copeland, a citizen of the United States, residing at New York, in the county and State of New York, have invented a new, original, and ornamental Design for a Vending Machine Cabinet, of which the following is a specification, reference being had to the accompanying drawing, forming part thereof.

Fig. 1 is a front view of a vending machine cabinet, showing my new design;

Fig. 2 is a side view of the cabinet shown in Fig. 1; and

Fig. 3 is a plan view of the cabinet.

The side of the cabinet not shown is identical to the side shown.

I claim:

The ornamental design for a vending machine cabinet, as shown and described.

PETER COPELAND.
